United States Patent

[19]

Schaefer et al.

[11] Patent Number: Des. 274,607

[45] Date of Patent: ** Jul. 10, 1984

[54] METAL DETECTOR

[75] Inventors: Edgar H. Schaefer, Louisville, Ohio;
William J. Wend, Sweet Home,
Oreg.

[73] Assignee: Teknetics, Inc., Lebanon, Oreg.

[**] Term: 14 Years

[21] Appl. No.: 352,240

[22] Filed: Feb. 25, 1982

[52] U.S. Cl. D10/47

[58] Field of Search D10/46, 47; 324/329,
324/327, 328

[57] CLAIM

The ornamental design for a metal detector, substantially as shown and described.

DESCRIPTION

FIG. 1 is an isometric view of a metal detector showing our new design;

FIG. 2 is a left end elevational view thereof;

FIG. 3 is a right end elevational view thereof;

FIG. 4 is a top plan view thereof;

FIG. 5 is a front side elevational view thereof, the rear side being a mirror image thereof;

FIG. 6 is a bottom plan view thereof.

Fig. 4.

Fig. 5.

Fig. 6.
